DESIGN FOR A BADGE

Eva Bradley, Arlene R. Adkin, and Joseph B. Clearihue, Victoria, British Columbia, Canada

Application February 11, 1941, Serial No. 98,918

Term of patent 7 years

To whom it may concern:

Be it known that we, Eva Bradley, Arlene R. Adkin, and Joseph B. Clearihue, all British subjects and residents of Victoria, Province of British Columbia, Dominion of Canada, have invented a new, original, and ornamental Design for a Badge, of which the following is a specification, reference being had to the accompanying drawing forming part thereof.

Figure 1 is a perspective view of the face of a badge, showing our new design;

Figure 2 is a front elevation;
Figure 3 is a side elevation; and
Figure 4 is a perspective view showing the back of the same.

We claim:

The ornamental design for a badge, as shown.
EVA BRADLEY.
ARLENE R. ADKIN.
JOSEPH B. CLEARIHUE.
